[57] CLAIM

The ornamental design for a support base for a camera or similar article, as shown and described.

DESCRIPTION

FIG. 1 is a perspective view of a support base for a camera or similar article showing our new design.

FIG. 2 is a top plan view thereof.

FIG. 3 is a bottom plan view thereof.

FIG. 4 is a side elevational view thereof showing the side opposite that shown in FIG. 1.
